His ATTORNEY

UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING SYSTEM.

Original application filed December 31, 1920, Serial No. 434,319. Divided and this application filed June 17, 1922. Serial No. 569,140.

To all whom it may concern:

Be it known that I, LLOYD V. LEWIS, a citizen of the United States, residing at Edgewood Borough, in the county of Allegheny and State of Pennsylvania, have invented certain new and useful Improvements in Railway-Traffic-Controlling Systems, of which the following is a specification.

My invention relates to railway traffic controlling systems, and particularly to systems of the type comprising traffic governing apparatus including means on a train arranged to change gradually from an initial condition to an ultimate condition.

15 The present application is a division of my co-pending application filed December 31, 1920, Serial No. 434,319, for railway traffic controlling systems, which latter is a continuation of my application filed April 24, 1918, Serial No. 230424, for railway traffic controlling systems.

I will describe one form of apparatus embodying my invention, and will then point out the novel features thereof in claims.

20 In the accompanying drawings, Fig. 1 is a diagrammatic view showing a stretch of railway track having applied thereto one form of trackway apparatus embodying my invention. Fig. 2 is a view, partly diagrammatic, showing one form of vehicle-carried apparatus embodying my invention and which may be used in conjunction with the trackway apparatus shown in Fig. 1.

Similar reference characters refer to similar parts in each of the views.

Referring first to Fig. 1, the reference characters 1 and 1^a designate the track rails of a railway over which traffic normally moves in the direction indicated by the arrow, and which rails are divided into block sections A—B, B—C, etc., by insulated joints 2. Each section is provided with a track circuit comprising a battery 5 and a relay R.

45 In the form here shown, sections A—B, B—C, and E—F constitute "positive control territory," while sections C—L and L—E constitute "non-positive control territory". Each of the sections in the positive 50 control territory is provided with two trackway magnets M, M arranged in longitudinal

alignment and preferably located between the track rails 1 and 1^a. The magnets M of each section are connected in multiple and are energized by a battery 50, the circuit 55 being controlled by a back contact 53 of the track relay R for the same section and by a front contact 52 of the track relay for the section next in advance. The magnets M in any one section are, therefore, energized only 60 when a train occupies the section and the next section in advance is unoccupied.

For reasons which will appear hereinafter, I provide at location C a track magnet M' similar in construction to the magnets M 65 but preferably located upon the outer side of one of the track rails so as to be out of alignment with the magnets M. This magnet M' is energized by the adjacent battery 50 through a back contact 53 of relay R for 70 section C—L. Furthermore, section E—F is provided with a ramp rail Z arranged at one side of the track rails and in advance of the first magnet M of that section.

Referring now to Fig. 2, the apparatus 70 here shown comprises a clearing magnet N and a cut-out magnet N', which are so mounted on the train as to have their poles disposed in confronting relation to the poles of the track magnets M and M' respectively. 80 Hence, as a train magnet passes over an energized track magnet, a current impulse is induced in a circuit including a coil 34 or 34^a surrounding the train magnet. Such an impulse in the clearing magnet N energizes 85 a relay P which in turn closes its contact 35 to complete a pick-up circuit for a stick relay P³, this pick-up circuit being from battery 60, through wires 100 and 101, contact 35, wire 102, relay P³, wire 103, circuit controller U³, wire 104, to battery 60. The holding circuit for relay P³ is from battery 60 through wires 100 and 105, contact 55 of relay P³, wires 54 and 102, relay P², wire 103, circuit controller U² and wire 104 to 95 battery 60. A contact 56 of relay P² controls the supply of current from battery 60 to a magnet Q², through the following circuit: from battery 60, wires 100 and 105, contact 56, wire 106, magnet Q², wires 107 100 and 108, to battery 60. Magnet Q² controls the supply of fluid pressure to a cylinder 61

so that this cylinder is connected with a source of fluid pressure or with atmosphere according as magnet Q^2 is energized or de-energized. A brake magnet Q , controlling a brake application valve 16, is connected to battery 60 through circuit controllers U' and U^2 and is normally energized to prevent application of the brakes. The circuit for magnet Q is as follows: from battery 60, 10 through wires 108, and 109, magnet Q ; wire 110, circuit controllers U' and U^2 in multiple, wire 111 to battery 60. When magnet Q is energized it holds valve 16 in the closed position, thereby preventing the exhaust of 15 fluid pressure from a brake control pipe 17 and so preventing an automatic application of the brakes. When, however, magnet Q is de-energized, it allows valve 16 to open, whereupon the fluid pressure in pipe 17 20 flows out to atmosphere through a port 18, thus causing an application of the brakes.

Circuit controllers U' and U^2 are operated by a run-down device J which is geared to an axle of the train, while circuit controller U^2 is operated by a centrifugal device J' . The run-down device J includes cylinder 61 in which is mounted a piston 62 having a piston rod 62^a extending into a casing 63. Slidably mounted in 30 the casing 63 is a rack bar 64 which is connected to the piston rod 62^a. The rack bar 64 is operatively connected to a shaft 65 by means of a pinion 66 keyed to the shaft and meshing with the toothed 35 surface of the rack bar. The shaft 65 extends through a slot 68 in the rack bar 64 and is keyed to a gear 69 which meshes with a pinion 70 keyed to a shaft 71. On shaft 71 is also mounted a ratchet clutch 73, comprising a spider 67 fastened to shaft 71 and a ring gear 72 which is free to turn on shaft 71 except that its motion in one direction is prevented by the wedging action of rollers 79^a located between spider 67 and 40 the inner face of gear 72. The gear 72 meshes with a worm 74 secured to a shaft 75, and this shaft carries a gear 76 which is connected to an axle of the train. It will be seen from this construction that upward 45 movement of the rack bar is unimpeded, while downward movement thereof is permitted only in accordance with the progress of the train along the track.

Secured to the upper end of the rack bar 55 64 is an insulated arm 78 which is engageable with the controllers U' and U^2 when the bar is in its highest and lowest positions respectively.

The centrifugal device J' is arranged up- 60 on one end of the shaft 75, and actuates a rod 77 which opens the circuit controller U^2 against the action of a spring 79 when the speed of the train exceeds a certain safe low value.

65 When the train approaches a track mag-

net M , the run-down device J is at or near its lowest position, so that circuit controller U' is closed. Then as magnet N passes over magnet M , if the latter is energized a momentary current will be induced in the circuit of relay P which will cause momentary energization of this relay. The consequent closure of contact 35 will close the pick-up circuit for relay P^3 , and the latter relay will then remain closed, due to its holding circuit, as long as circuit controller U^2 remains closed. Relay P^3 , by the closing of contact 55 75, will energize clearing magnet Q^2 , whereby fluid pressure is admitted to cylinder 61 to move the rack bar 64 to its uppermost 80 position. When the rack bar reaches this position, arm 78 will open circuit controller U' which opens the holding circuit of relay P^3 . Relay P^3 then opens, and so de-energizes magnet Q^2 , which permits the fluid pressure in cylinder 61 to exhaust to atmosphere, thus allowing rack bar 64 to descend under the influence of gravity. The downward movement, however, is limited by the rotation of the train axle, hence the train 90 may proceed at unretarded speed for a predetermined distance, that is, for the distance required for arm 78 to reach contact U' . This distance is somewhat greater than the distance from one magnet M to the next 95 magnet M in advance. If, therefore, the train should proceed at high speed and should fail to receive an impulse from a track magnet before the rack bar 64 reaches its lower position, circuit controller U' will 100 be opened to de-energize magnet Q and so to apply the brakes. It will be apparent, therefore, that to permit the train to proceed at unretarded speed and to prevent the application of the brakes by the descent of 105 rack bar 64, it is necessary that magnet M should receive impulses at predetermined intervals somewhat less than the interval required for the rack bar to run down. However, assuming that a magnet M is de-energized, and that rack bar 64 is permitted to move to its lower position wherein the arm 78 opens the circuit controller U' , the train may still proceed 110 at a safe low speed without an application of the brakes because of circuit controller U^2 . This controller is in multiple with controller U' , hence brake magnet Q will be de-energized only when both of the circuit controllers are open. Circuit controller U^2 is 120 opened only when the speed of the train exceeds a safe low speed determined by the resisting action of the spring 79 upon the centrifugal device. The train may, of course, resume normal speed upon reaching 125 the next energized track magnet M .

The cut-out magnet N' controls a mechanical device comprising a cylinder 29 in which moves a piston 20. Attached to the piston is a rod 20^a whose lower end pro- 130

- jects beyond cylinder 19 and is provided with a contact shoe 22. Rod 20^a is encircled by a helical spring 21 which tends to retract the rod 20^a and contact shoe 22 to the position shown in full lines in the drawing. The rod may, however, be moved to a projected position to lower the shoe 22 to the position indicated by dash lines, by means of air pressure, which is conveyed 10 to the cylinder 19 from a supply reservoir (not shown) through a supply pipe 23. The supply of air to cylinder 19 is controlled by a valve 25 which in turn is governed by the armature 24 of a magnet Q'. When 15 this magnet is de-energized, valve 25 is held in the position shown by a spring 26, and cylinder 19 is then open to atmosphere through an exhaust port 27, so that the shoe 22 occupies its upper or retracted position. When magnet Q' is energized, however, valve 25 is reversed so that air pressure is then admitted to the cylinder 19 through pipe 23 to project the piston 20 and shoe 22 downwardly against the action 20 of the coil spring 21. The piston rod 20^a carries an arm 20^c to which one end of a link 20^b is pivotally connected. The other end of this link is pivotally connected to a crank 20^d which is attached to a rotary 25 switch member 28. This member is provided with diametrically opposite contact segments 28^a which are electrically connected as shown. Bearing on the periphery of the switch member 28, at diametrically opposite points, are contact brushes 29, 29^a which are electrically connected by means of the segments 28^a when the rod 20^a is in its projected position but not when in retracted position.
30. The cut-out magnet N' carries a winding 34^a the circuit for which includes a relay P', so that when the train passes over magnet M' this relay is momentarily closed. While relay P' is closed it energizes a relay P⁴ through the following circuit: from battery 60 through wires 100 and 59, contact 41 of relay P', wire 94, relay P⁴, wire 96, back contact 93 of relay P², wires 97, 98 and 108 to battery 60. Relay P⁴ then remains energized due to its holding circuit, which is from battery 60 through wires 100 and 135, contact 57, wires 95 and 94. Relay P⁴, wire 96, back contact 93, wires 97, 98 and 108, to battery 60. Magnet Q' then becomes energized through the following circuit: from battery 60 through wires 100 and 135, contact 58, wires 136 and 137^a, magnet Q', wires 99, 98 and 108, to battery 60. When contact shoe 22 is moved to its projected position, due to the energization of magnet Q', a branch circuit is closed in multiple with magnet Q' through wires 137 and 139, contact 29^a-28-29, wire 138, relay P², wire 99 to wire 98, thus energizing relay P². When relay P² picks up, it remains energized by virtue of a circuit from battery 60 through wire 100, contact 91, wire 139, contact 29^a-28-29, wire 138, relay P², wires 99, 98 and 108, to battery 60. The closing of relay P² opens the circuit of relay P⁴ at contact 93. Magnet Q' remains energized, however, because of a branch circuit from wire 100 through contact 91, wires 137 and 137^a, magnet Q', and wire 99^a to wire 98. Brake magnet Q then remains energized irrespective of the position of circuit controllers U' and U², by virtue of a circuit from battery 60 through wire 100, contact 92, wire 140, magnet Q, wires 109 and 108, to battery 60.
35. The operation of the apparatus thus far referred to in Figs. 1 and 2 is as follows: Assuming that section B-C of Fig. 1 is occupied, the relay R for that section will be de-energized and so will open the circuit of the track magnets M in section A-B. I will now assume that a train equipped with the apparatus of Fig. 2 enters section A-B at high speed. Since the first track magnet M of this section is de-energized, magnet N will not receive an impulse therefrom, hence the run-down device J will open contact U' and so will de-energize the brake magnet Q, thus causing an application of the brakes which will reduce the speed of the train to a low value. If, then, the train in section B-C passes out of that section, the track magnet M of section A-B will become energized, so that as the train passes the second magnet M of that section, relay P will be momentarily energized, thereby causing the run down device J to be restored to its initial position, and so permitting the train to resume full speed. The operation of the apparatus during the 105 passage of the train through section B-C is the same as during its passage through section A-B. As the train enters section C-L and the magnet M' passes over the track magnet M', relay P' will be momentarily energized to cause energization of relay P⁴ and magnet Q', whereby the shoe 22 will be projected and relay P² will be energized, thus rendering contacts U' and U² ineffective to cause de-energization of the brake magnet Q. As the positive control means is now ineffective to retard the train, the train may proceed through the non-positive control territory at unrestricted speed, except for the influence of an intermittent control ramp as hereinafter explained. When, however, the train enters section E-F, which is in the first section of another positive control territory, the shoe 22 will engage the ramp rail Z and so 120 will be forced inwardly to open contact 29-28-29^a; this will open relay P² whereby the run down device J will be restored to

its control of the brake magnet Q by the opening of contact 92 of relay P². It will be noted, however, that a track magnet M is interposed between the entrance end of the section E—F and the ramp Z so that if the section to the right of E—F is unoccupied the train may proceed at full speed after passing the ramp.

Referring again to Fig. 1, the non-positive control territory C—E is provided with means for the intermittent control of trains in accordance with traffic conditions therein. As here shown, this is accomplished by a signal and a ramp. Section L—E of this territory is provided with a home signal H^L located at the entrance end of the section and controlled by the track relay R^L at the same location, so that this signal indicates proceed or stop, according as section L—E is unoccupied or occupied. Section L—E is also provided with a distant signal which is designated by the reference character D^L and is located at least at maximum braking distance in the rear of the entrance end of the section. This distant signal is controlled by the track-relay R^L for section L—E and so it indicates proceed or caution according as section L—E is unoccupied or occupied.

Section L—E is further provided with a ramp which is located adjacent the distant signal, and is designated by the reference character Z^L. This ramp co-operates with the train-carried contact shoe 22 shown in Fig. 2, when the shoe is in projected position, and the supply of current to each ramp is controlled by the track relay R^L for the section L—E. When shoe 22 is on ramp Z^L and relay R^L is closed, an auxiliary circuit for relay P² is closed, which circuit is as follows: from trackway battery 42, through wires 143 and 145, rail 1, wheel 146, axle 147, contact 148, wire 37, winding of relay P², wire 33, shoe 22, ramp Z^L, wires 144, 57 and 45, track relay contact 49, and wire 141 to battery 42. It follows from the foregoing that when the train passes over the intermittent control ramp Z^L, relay P² will be kept energized if the ramp is energized, so that the train may proceed at full speed without retardation; if the ramp is not energized, however, the opening of contact 29—28—29^a, due to the elevation of shoe 22, will permit relay P² to become de-energized, in which event the train will be brought to a stop or to the predetermined low speed before entering section L—E.

Although I have herein shown and described only a few forms of railway traffic controlling systems embodying my invention, it is understood that various changes and modifications may be made therein within the scope of the appended claims without departing from the spirit and scope 65 of my invention.

Having thus described my invention, what I claim is:

1. In combination, a railway train, speed-responsive means thereon, governing means on the train controlled by said speed-responsive means, an element on the train adapted to change constantly towards an ultimate condition and operating in all conditions except its ultimate condition to remove said governing means from control by said speed-responsive means, and devices located in the trackway and controlled by traffic conditions in advance for restoring said element away from ultimate condition, said element being adapted after each restoration to automatically resume its change towards its ultimate condition.

2. In combination, a railway train, governing apparatus thereon including means arranged to change gradually from an initial condition to an ultimate condition, mechanism on the train including a magnet adapted when the magnet is energized to restore said means away from ultimate condition, a normally open relay on the train, a circuit for said magnet controlled by a front contact of said relay, a second normally open relay on the train, a pick-up circuit for said first relay controlled by a front contact of said second relay, a stick circuit for the first relay including a front contact of the first relay itself and a normally closed contact which is opened when said means is restored to its initial condition, a circuit for said second relay including a winding, and devices located at intervals in the trackway for momentarily inducing current in said winding.

3. In combination, a railway train, governing apparatus thereon including means arranged to change gradually from an initial condition to an ultimate condition, mechanism on the train including a magnet adapted when the magnet is energized to restore said means away from ultimate condition, a normally open relay on the train, a circuit for said magnet controlled by a front contact of said relay, a second normally open relay on the train, a pick-up circuit for said first relay controlled by a front contact of said second relay, a stick circuit for the first relay including a front contact of the first relay itself and a normally closed contact which is opened when said means is restored to its initial condition, a circuit for said second relay including a winding on a magnetic core, and other magnetic cores located in the trackway each provided with a winding and each adapted when the winding is energized to induce a current in the train carried winding and so to momentarily close said second relay.

4. In combination, a railway train, speed-responsive means thereon, governing means on the train controlled by said speed-re-

sponsive means, an element on the train adapted to change constantly towards an ultimate condition and operating in all conditions except its ultimate condition to
5 remove said governing means from control by said speed-responsive means, and devices located in the trackway and controlled by traffic conditions in advance for restoring said element away from ultimate condition, said element being adapted after each restoration to automatically resume its change towards its ultimate condition.

In testimony whereof I affix my signature.

LLOYD V. LEWIS.
